UNITED STATES PATENT OFFICE.

JOHN A. BOYCE, OF SPRINGFIELD, ILLINOIS.

PRINTING-MACHINE.

No. 924,310.

Specification of Letters Patent.

Patented June 8, 1909.

Application filed April 3, 1908. Serial No. 425,058.

To all whom it may concern:

Be it known that I, JOHN A. BOYCE, a resident of Springfield, in the county of Sangamon and State of Illinois, and a subject of 5 His Majesty Edward VII, King of Great Britain and Ireland, have declared my intention to become a citizen of the United States, as evidenced by the certificate of the county clerk of Sangamon county, Illinois, now on 10 file in the Patent Office.

Be it further known that I have invented certain new and useful Improvements in Printing-Machines, of which the following is 15 such a full, clear, and exact description as will enable others skilled in the art to which it appertains to make and use my said invention.

This invention relates to rotary perfecting machines adapted to print upon both sides 20 of continuously moving webs, and equipped with plates having columns circumferential to the plate cylinders.

A prime purpose of this invention is to provide mechanism adapted to produce a 25 page for plate product, in continuous straight run; that is to say; to produce ten pages from ten plates, twelve pages from twelve plates, fourteen pages from fourteen plates, sixteen pages from sixteen plates, and so on; a complete paper in book form being produced for 30 each half revolution of the plate cylinders with all of the printing couples operating at full speed.

Another purpose of this invention is to 35 provide mechanism adapted to produce a complete paper in book form or in sections consisting of a page for plate product, either with a supplement or supplements, or without supplements, when all of the plate cylinders and all of the impression cylinders are 40 operating at full speed.

With these ends in view my invention consists in the novel features of construction and 45 combinations of parts shown in the annexed drawings to which reference is hereby made; and hereinafter particularly described and finally recited in the claims.

Inasmuch as this invention relates primarily to the relation of the mechanisms, and 50 the mechanisms themselves are of the usual well known constructions except where otherwise specified; the drawings are in the nature of diagrams showing the relation of the mechanisms.

55 This invention contemplates the use of

plate cylinders equipped with half a complement of plates around the cylinders to operate upon a single web, to produce a page for plate product in book form.

It also contemplates the use of plate cylinders equipped with a full complement of plates around the plate cylinders to operate upon a single web to produce papers in sections collected, that is to say; if book form papers, not collected, are produced, half a 60 complement of plates around the cylinders may be used, or a full complement of plates around the cylinders may be used, and if sections are collected a full complement of 65 plates around the cylinders will be used. 70

This invention also contemplates the location of the blanket cylinders and the ink drums in such position as not to interfere with the handling of plates in putting the plates on or taking them off from the plate cylinders and the adjusting of the blanket cylinders relative to the plate cylinders as hereinafter set forth to admit of operation with plate cylinders equipped with half a complement of plates or plate cylinders 80 equipped with a full complement of plates, as may be preferred.

In this application no claim is made to the means for actuating the various cylinders and rollers of the machine and it is to be 85 understood that they may be actuated by any suitable system of gears. The plate cylinders, blanket cylinders and ink drums may be of any suitable width, and of any 90 approved construction.

In order that this invention may be clearly understood it is necessary to briefly set forth the prior state of the art as follows: Printing machines equipped with plate cylinders having plates circumferential to the plate 95 cylinders are of two classes which for convenience in description I will designate as class A and B, respectively. In class "A" machines a number of webs are brought together over a former and the first fold is 100 made on the former and the cutting and second folder devices are situated below the former. In such a machine it is necessary to have two plates of the same matter lying end to end around the plate cylinders, in order to 105 get a complete paper in book form for one half turn of the printing couples. It is obvious therefore that such a machine must have twice as many stereotype plates as there are pages in a book form paper, in order 110

to get a high speed. Class "B" machines also are equipped with formers for making the first fold. The main sheets from a web or webs running from one or more decks of the machine are cut and collected before the first fold is made on the former and if there is a two-page supplement sheet inserted between the leaves, the supplement deck of the press must run at half speed; four stereotype plates will therefore be required to produce the two page supplement sheet. It will therefore be seen that in a class "B" machine operating as described, twelve plates are required to produce a ten page paper in book form; and sixteen plates to produce a fourteen page paper in book form; and so on. A class "B" machine equipped to produce ten-page papers in book form must collect the cut sheets before making the first fold, and must use twelve plates, of which eight are for main pages and four are for supplement pages; and the supplement plate cylinders must run at half speed in order that the main sheets may be collected and the supplements inserted with the collected sheets. This collecting of the main sheets retards the operation to such extent that if collecting is done only half as many papers per hour can be produced as would be produced if the machine were running on book-form papers without supplements; for example, if the maximum product of a class "B" machine operating on book-form papers without supplements (say eight-page papers) is twenty thousand papers per hour, its product when operating to produce papers comprising collected main sheets, with inserted supplements (say ten-page papers) will be only half of the original product; that is to say, ten thousand papers per hour. My machine equipped to produce a ten-page paper will operate all of the cylinders at full speed and will have only ten plates as against the twelve plates of the class "B" machine. It is obvious therefore that my machine of a given maximum full-speed capacity when operating on papers with supplements will produce twice the number of papers per hour, from a less number of plates, than a class "B" machine operating on the same kind of papers can produce in the same time.

Referring to the drawings in which similar reference letters and characters designate like parts in the several views; Figure 1 is a diagram showing in elevation plate cylinders, blanket cylinders, etc., arranged to operate upon a single web with half a complement of plates around the plate cylinders. Fig. 2 is a similar diagram showing the same mechanisms adjusted to operate upon a single web with a full complement of plates around the plate cylinders. Fig. 3 is a diagram showing in top plan the relation of the plate cylinders, blanket cylinders, ink-drums, web adjusters, angle bars and former. The ink-

ing rollers, form rollers and other minor details are omitted from this view and some of the cylinders are shown as broken away to expose underlying parts. This view also shows the preferable arrangement of a half complement of plates on the plate cylinders. Fig. 4 is an enlarged isometric projection of one of the adjusting devices used for adjusting the position of the blanket cylinders relative to the plate cylinders and for controlling the pressure on the plate cylinders and Fig. 5 is an enlarged partial isometric projection of the web adjusting devices.

Revolute plate cylinders P and P' of usual construction are of diameter suitable to accommodate two plates end to end extending around the cylinder and may be any suitable number of plates in width.

The revolute blanket cylinders, B , B' , B'' , and the revolute ink drums I , I' , I'' and I''' are all of the usual construction and are half the diameter of a plate cylinder but may be of different diameter without departure from my invention.

The ink drums I , I' , I'' and I''' are so located relative to the plate cylinders that ink is applied at every half revolution of the plate cylinder and it is therefore unnecessary to change the inking devices either when there is a half complement of plates or a full complement of plates in use on the plate cylinders.

Revolute distributing rollers d , run in contact with the ink drums and distribute the ink in the usual well known manner and revolute form rollers f of the usual construction apply the ink on the face of the plates in the usual well known manner. A paper roll R , mounted in the usual manner supplies the web to be operated upon.

In case the plate cylinders are equipped with a half complement of plates I prefer a zigzag arrangement of the plates on the cylinder, such as is shown in Fig. 3.

The plates being arranged as described, plates 1, 3 and 5 will print upon the upper surface of the web running on the cylinder B during the first half revolution of the plate cylinder; and will print upon the upper side of the same web running upon the cylinder B' during the second half of the revolution of the cylinder P ; and the plates 10 and 8, will print upon the upper surface of the web running on the cylinder B during the second half of the revolution of the cylinder P and the same plates will print upon the upper surface of the same web running upon the blanket cylinder B' about the same time that the plates 1, 3 and 5 are printing upon the upper surface of the web running on the cylinder B . Or the plates may be arranged in a straight row side by side across the plate cylinder and occupying one half the circumference of each plate cylinder; the plates of pages 1, 10, 3, 8 and 5 being placed on one

semi-circumference of the cylinder P and the plates of pages 2, 9, 4, 7 and 6 being placed on one semi-circumference of the cylinder P'.

A practical advantage of placing the plates 5 zig-zag on the cylinders, as shown in Fig. 3, is that there is always plate surface in contact with both of the impression cylinders B and B', and the cylinders therefore run more evenly than they would run if the plates were 10 at any time in contact with only one of the impression cylinders.

In order that the blanket cylinders may run in contact with the plate cylinders when the blanket cylinders serve as impression 15 cylinders and may run free from the plate cylinders when the blanket cylinders are not in use as impression cylinders, adjusting devices for adjusting the blanket cylinders relative to the plate cylinders are provided. 20 There is an adjusting device at each end of each blanket cylinder and all of said adjusting devices are exactly alike; so a description of one will suffice for all. I will now describe one of said adjusting devices.

25 A box A is fixed on the main frame of the printing machine. A block A' is slideable in suitable guides in the box A. The shaft b of the blanket cylinder B turns in a suitable bearing in the block A'. The block A' has a 30 central female screw a in which the screw threaded part d of the bolt D fits. The bolt D extends through a fixed standard A³ on the main frame and has screw threaded parts d and d' and a square part d''. A collar d³ is 35 secured on the bolt D. A nut d⁴ and a jam nut d⁵ fit on the part d' and a jam nut d⁶ fits on the part d. A forked key E straddles the bolt D and fits between the collar d³ and the upright A³. A set screw e extends through 40 the key E and bears against the upright A³ and serves to keep the key in position.

If it be desired to move the block A' quickly to bring the cylinder B into contact with the plate cylinder, or to move it away 45 from the plate cylinder, the set screw e will be loosened and the key E will be withdrawn and the bolt D will be slid inward or outward to slide the block A' so as to bring the circumference of the cylinder B into contact 50 with the circumference of the plate cylinder, or to move it away from the plate cylinder as the case may be; and when the blanket cylinder is properly adjusted the key E may be placed on either side of the upright A³ and 55 secured to hold the block A' in the position in which it may be set.

If it be desired to increase the pressure of the blanket cylinder on the plate cylinder the nut d⁶ will be loosened and the bolt D will be 60 turned by any suitable instrument fitting on the squared part d⁷ to cause the screw part d to move inward or outward in the female screw a to place the block in position to produce the desired pressure of the blanket cylinder against the plate cylinder; and the nut 65

d⁶ will then be tightened to secure the parts in the position in which they are set.

From the foregoing it will be seen that the box A' may by the instrumentality of the key or wedge E be quickly moved to bring 70 the blanket cylinder in contact with the plate cylinder or to place it out of contact with the plate cylinder and may by turning the bolt, be nicely adjusted to regulate the pressure of the blanket cylinder against the plate 75 cylinder.

In practice the plate cylinders P and P' will be so located that pages printed by the cylinder P' coöperating with the blanket cylinder B² will register with pages printed by the 80 cylinder P coöperating with the blanket cylinder B'.

It will be observed that the blanket cylinders B and B' are both on one side of the diameter X of the plate cylinder P; and the 85 blanket cylinders B² and B³ are both on one side of the diameter Y of the plate cylinder P'; it is obvious therefore that access to one half of each plate cylinder is unobstructed and there is nothing to interfere with the 90 handling of the plates. This feature is of great practical advantage.

I am aware that duplicate blanket cylinders and duplicate inking devices have been used in coöperation with a single plate cylinder equipped with a full complement of plates, but the parts have hitherto been so arranged that either the blanket cylinders or the inking devices interfere with the handling of the plates. In my machine this objection is overcome.

As has already been stated the cylinders B' and B² are so situated that the pages printed by said cylinders coöperating with the plate cylinders will register with each other. 105

In order to attain perfect registration of the pages impressed upon the web running upon the cylinders B and B³ in coöperation with the cylinders P and P' respectively, it is necessary to adjust the web running between said cylinders B and B³ to cause the proper locating of the pages on the web and to compensate for stretching or accidental moving of the web which might throw the pages out of registry, and it is also necessary 110 to so adjust the web that the pages impressed upon the cylinder B² will be upon the same side of the web and in line with the pages impressed upon the cylinder B³. I will now describe the mechanism for effecting 115 these adjustments of the web.

A fixed shaft G⁴ extends across the machine. Arms G and G² are mounted on the shaft G⁴. Rollers g² are mounted to turn in bearings on the arms G² and similar rollers g³ 125 are mounted to turn in bearings on the arm G. Set screws G³ connect the arms G² with the shaft G⁴ and similar set screws G' connect the arms G with the shaft G⁴. By loosening the set screws G³ the arms G² may be turned 130

on the shaft to raise or lower the roller g^2 ; and by loosening the set screws G' the arms G may be turned on the shaft to raise or lower the roller g^6 .

- 5 When the rollers g^2 and g^3 are placed in the desired position the set screws G^3 and G' will be screwed down to secure the arms on the shaft and hold the arms to support the rollers in the position in which they are set.
- 10 When operating upon a single web with a half complement of plates around the plate cylinders (Figs. 1 and 3) the operation will be as follows: The first impression will be made upon the cylinder B , the second impression will be made on the cylinder B^3 , the third impression will be made on the cylinder B^2 , and the fourth impression will be made on the cylinder B' . From the foregoing it will be seen that the first and fourth impressions will be on the upper side of the web; the second impression will be on the reverse side of the web and will back the first impression; and the third impression will be on the reverse side of the web and will back the fourth impression. The web from the roll R will run around the cylinder B and between the cylinders P and B and the first impression will be made on the upper surface of the web. After the cylinder P —when operating with half a complement of plates,—has printed upon the upper surface of the web running on the cylinder B the run of the web must be timed so that when the part of the web which is to be printed upon the cylinder B' arrives in position for the fourth impression to be made a blank space must be presented, otherwise the impression upon the cylinder B' would overlap the impression made by the cylinder B . After the first impression has been made the web will be led under the roller g , over the roller g' , under the adjusting roller g^3 , and under the roller g^4 , to adjust the pages to be impressed upon the cylinder B^3 to the pages previously impressed on the cylinder B , and will then run to the blanket cylinder B^3 , and between the cylinders P' and B^3 and the second impression will be made on the under or reverse side of the web; the web will then run around the rollers g^6 , g^5 , g^2 , and g^7 —to adjust the pages to be impressed on the cylinder B^2 to the pages previously impressed on the cylinder B^3 ,—and thence to the cylinder B^2 and between the cylinders P' and B^2 , and the third impression will be made on the under or reverse side of the web; and the web will then run from the cylinder B^2 to the cylinder B' and between the cylinders P and B' and the fourth impression will be made on the upper surface of the web in line with the first impression.

In operating with a full complement of plates around the cylinders P and P' web from the roll R (Fig. 2) will run over the rollers g' and g^7 to the blanket cylinder B^2 and

between the blanket cylinder B^2 and the plate cylinder P' and the first impression will be made on the under side of the web, the web will then run to the blanket cylinder B' and between the plate cylinder P and the blanket cylinder B' and the second impression will be made upon the upper surface of the web.

When a full equipment of plates is used and the run of the web is as shown in Fig. 2, the cylinders B and B^3 will be in disuse and will be moved outward, as shown so as not to contact with the cylinders P and P' . The web printed on both sides will then be led to the associating and first-folder device.

If the machine is operating with a half complement of plates around the plate cylinders the product will be a page for plate product in book form; and if the machine is operating with a full complement of plates around the cylinders all the plates will be original plates and the product, whether in book form or in sections collected, will still be a page for plate product. In every case the number of pages of the product will be equal to the number of plates of the printing couples.

The means for slitting the web, turning and associating the web members and folding longitudinally the two plate wide web members will now be described.

A revolute roller H extends across the machine above the impression cylinder B' . A horizontal revolute shaft K is parallel to the roller H . Circular slitter blades h are secured on the shaft K and slit the web longitudinally to divide it into three web members two of which are two plates wide and one of which is one plate wide. Fixed horizontal turner bars M of the usual construction are above and inclined at an angle of 45 degrees relative to the cylinder B' . A former N of usual construction is located in position to receive web members running on the turner bars. The one page-wide supplement web member is turned around one of the turner bars M and runs either between the main web members or next to the surface of one side of the former N . The two page-wide web members are turned around the other turner bars, respectively, and run to the former and are folded lengthwise by the former. The supplement web member being next to the surface of the former or between the two-page-wide web-members as the case may be, is situated between the leaves of one of the two page-wide web members. After the two page-wide web members have been run over the former and folded lengthwise as described the longitudinally folded web members will be cut into sheets by cutter mechanisms below the former, which are not part of the present invention and are therefore not shown or described, and said cut sheets will be folded by folder mechanisms which

are not part of this invention and therefore are not shown or described.

Having fully described my invention what I claim as new and desire to secure by Letters Patent is:

1. In a printing machine, the combination of a primary plate cylinder, impression cylinders coöperating with and separately adjustable relative to said primary plate cylinder, means for inking said primary plate cylinder, a secondary plate cylinder, impression cylinders coöperative with and separately adjustable relative to said secondary plate cylinder, means for inking said secondary plate cylinder, means for leading the web to receive the first impression from one of said plate cylinders, the next two impressions from the other plate cylinder and the final impression from said first-named plate cylinder, means for slitting the web to form one-page-wide and two-page-wide web-members, means for associating said web-members in parallel, and means for folding longitudinally and centrally said two-page-wide web-members.

2. Means effective to print upon a continuously moving web, a page-for-plate product by means of plate cylinders equipped with a half-complement of plates extending half-way around the plate cylinders, and equally effective to print by means of the same plate cylinders equipped with a full complement of plates extending entirely around the plate cylinders, a page-for-plate product having double the number of pages of said first named product; comprising a revoluble plate cylinder, a first impression cylinder and a fourth impression cylinder, coöperative with and adjustable relative to said plate cylinder, a complemental plate cylinder in operative relation to said first-named plate cylinder, a second impression cylinder and a third impression cylinder coöperative with and adjustable relative to said complemental plate cylinder, means for inking said plate cylinders and means for leading said web so that one side of the web will be perfected while running on the third impression cylinder and the other side of the same web will be perfected while running on the fourth impression cylinder, in case a half-complement of plates extending half-way around the plate cylinders is used and likewise in case a full complement of plates extending entirely around the plate cylinders is used.

3. Means effective to produce from a continuously moving plural-plate-wide web, a page-for-plate product including supplement, by means of plate cylinders equipped with a half complement of plates extending half-way around said plate cylinders and equally effective to produce by means of the same plate cylinders equipped with a full complement of plates extending entirely around said plate cylinders, a page-for-plate

product having double the number of pages of said first named product; comprising a revoluble plate cylinder, a first and fourth impression cylinder coöperative with and adjustable relative to said plate cylinder, a complemental plate cylinder in operative relation to said first named plate cylinder, a second impression cylinder and a third impression cylinder coöperative with and adjustable relative to said complemental plate cylinder, means for inking said plate cylinders, means for leading said web so that one side of said web will be perfected while running on the third impression cylinder and the other side of the same web will be perfected while running on the fourth impression cylinder, in case a half-complement of plates extending half-way around the plate cylinders is used and likewise in case a full complement of plates extending entirely around the plate cylinders is used, means for dividing said continuously moving web into a one-plate-wide and a two-plate-wide web-member and effecting a quarter turn thereof to associate in parallel said one-plate-wide and two-plate wide web-members, and means for folding longitudinally said two-plate-wide web-member.

4. Means effective to produce from a continuously moving web a page-for-plate product by means of plate cylinders equipped with a half-complement of plates extending half-way around the plate cylinders, and equally effective to produce by means of the same plate cylinders equipped with a full complement of plates extending entirely around the plate cylinders a page-for-plate product having double the number of pages of said first named product; comprising a revoluble plate cylinder, a first and fourth impression cylinder coöperative with and adjustable relative to said plate cylinder, a complemental plate cylinder in operative relation to said first named plate cylinder, a second impression cylinder and a third impression cylinder coöperative with and adjustable relative to said complemental plate cylinder, means for inking said plate cylinders, means for leading said continuously moving web so that one side of the web will be perfected while running on the third impression cylinder, and the other side of the same web will be perfected while running on the fourth impression cylinder, in case a half-complement of plates extending half-way around the plate cylinders is used, and likewise in case a full complement of plates extending entirely around the plate cylinders is used, means for effecting a quarter turn of said continuously moving web, and means for folding longitudinally said continuously moving web.

5. The combination of a revoluble plate cylinder, a revoluble impression cylinder mounted in slideable supports and adapted to

- coöperate with said plate cylinder, screws
slidable longitudinally in stationary supports
and respectively connected with the slidable
supports of said impression cylinder and
adapted to be turned to move said slidable
supports slightly for accurate adjustment of
said impression cylinder, and keys adapted
to engage with said screws respectively, to
limit the sliding of said screws in one direc-
10 tion to bring said impression cylinder into
use and adapted to engage with the same
screws to limit the sliding of said screws in
the opposite direction to place said impres-
sion cylinder in dis-use.
- 15 6. In a printing machine the combination
of two parallel revoluble plate cylinders ef-
fective to print on both sides of a single web
and adapted to accommodate a half comple-
ment of plates extending half-way around
20 said plate cylinders respectively, or a full

complement of plates extending entirely
around said plate cylinders respectively; four
impression cylinders coöperating with said
plate cylinders to perfect a continuously
moving web in case a half complement of 25
plates is used on said plate cylinders; and
means for placing out of commission two of
said impression cylinders and leaving two of
said impression cylinders in commission and
coöperating with said plate cylinders to per-
fect a continuously moving web in case a full
complement of plates is used on said plate
cylinders. 30

In witness whereof I have hereunto signed
my name at Springfield, Illinois, this 30th 35
day of March, 1908.

JOHN A. BOYCE.
